UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

CAN-CAP-LINING APPARATUS.

Application filed March 5, 1923. Serial No. 622,732.

To all whom it may concern:

Be it known that I, JOHN M. HOTHERSALL, a citizen of the United States, residing in Brooklyn, in the county of Kings and State 5 of New York, have invented a new and useful Improvement in Can-Cap-Lining Apparatus, of which the following is a specification.

My invention relates to apparatus for 10 lining can covers, or the like, with a gasket material such as combined paper or felt and tin foil. In the type of container which is closed by a screw closure and adapted to contain oil or other liquid contents, it is 15 necessary that the closure be lined with a material of this character which ordinarily is applied in the form of a disk seated in the top of the closure and adapted to be brought down upon the neck of the can to prevent 20 leakage when the latter is closed. My invention contemplates the provision of apparatus for not only forming strips of the desired combination of materials, but also for cutting out disks or liners from the formed 25 strip and applying them to the covers.

It is also an object of the invention to provide means for controlling the feeding of the liner material so that no liner is cut therefrom when there is no cover advanced 30 to position to be lined.

Another object is the provision of a machine unit adapted to perform the several operations necessary to form and apply liners of this character in fully automatic 35 and efficient manner and by the utilization of a single source of power.

Other objects and advantages of the invention will be apparent as it is better understood from the following description, which, 40 taken in connection with the accompanying drawings, discloses a preferred embodiment thereof.

Referring to the drawings.

Figure 1 is a general side elevation of 45 the apparatus in which my invention is embodied;

Fig. 2 is a side elevation showing more in detail the construction of the strip feeding and liner applying machine;

Fig. 3 is a front elevation of said machine; 50 Fig. 4 is a plan view of the bed of the machine, being taken through the frame substantially on the section line 4-4 in Fig. 3;

Fig. 5 is an enlarged section taken substantially on the line 5-5 in Fig. 3;

Fig. 6 is an enlarged section taken substantially on the line 6-6 in Fig. 4;

Fig. 7 is an end elevation of the glue applying apparatus;

Fig. 8 is a top plan view thereof; 60

Fig. 9 is an enlarged elevation of the glue receptacle and rollers, partially broken away and sectionalized, substantially on the line 9-9 in Fig. 7;

Fig. 10 is a detail sectional view, taken 65 substantially on the line 10-10 in Fig. 4; and

Fig. 11 is a section taken substantially on the line 11-11 in Fig. 4.

The apparatus as illustrated comprises 70 two main units, namely the feed and punch press 11 and a gluing machine 12. The latter consists of a supporting frame 13, in

the lower part of which there is mounted a drum 14 upon which is wound a supply of 75 paper, felt, or other suitable material which is adapted to be directed upwardly over a roller 15 and between rollers 16 and 17, the former being mounted to pass through a glue receptacle 18 as it revolves. Said 80

drum 14 is secured upon a transverse shaft 19 rotatably supported in bearing brackets 21 on the frame 13. The roller 15 has bearings in a bracket 22 on the frame 13 and a second roller 23 is mounted in the upper 85

part of said bracket. The roller 16 is supported upon point bearings 24 provided in upstanding brackets 25 at the sides of the receptacle 18, and a scraper 26 is positioned upon a cross piece 27 (Figs. 8 and 9) in such 90

manner that the roller 16 passes between side fingers 28 on said scraper. An upper guide 29 is provided above the scraper and serves to direct a strip 31 onto the roller 16. Said scraper is adjustably secured in 95 place by means of a screw 32 and serves to control the amount of glue adhering to said roller 16 as the latter turns

having turned out of the glue receptacle 18 applies glue to the strip 31. The roller 17 100 is mounted in side brackets 33 and is pro-

vided with a groove 34 in which the strip 31 is held as the glue is applied thereto by the roller 16. The strip 31, with glue applied thereto, is directed over the roller 23 and

between feed rolls 35 and 36 (Fig. 5) in the press 11. A drain pipe 40 may be provided at the bottom of the receptacle 18, and is normally closed by a cap 40' or in any 105

suitable manner.

Said press 11 is supported on a base 37 by means of a frame 38, which latter is adjustably secured in said base by means of bolts 39 taking through slots 41. A drum 42, mounted in brackets 43 in the upper part of the frame 38, contains a supply of tin foil, or the like, which is fed between the rollers 35 and 36, the tin foil strip 44 being directed between said rollers above against the side of the paper or felt strip 31 to which the glue has been applied. In this manner, the strips are glued together and the resulting duplex strip advanced to the gasket punching and applying station.

Said feed rolls 35 and 36 are operated from a rock shaft 45 by mechanism to be now described. The roller 35 is carried on a shaft 46, which is rotated by means of a ratchet device 47 connected by a rod 48 with parts carried upon the shaft 45. Said ratchet device consists of a collar 49 fitting upon a sleeve 51 mounted on the shaft 46, said sleeve being provided with a plurality of recesses 52 of wedge formation, the latter having rollers 53 disposed therein and adapted to ride outwardly in said recesses when the collar 49 is moved in counterclockwise direction, viewing Fig. 2. When turned in clockwise direction, it will be manifest that the rollers 53 are moved inwardly in the recesses 52 and the collar 49 is allowed to turn relatively to the sleeve 51 without turning the shaft 46.

The rock shaft 45 is driven from a main power shaft 54 by means of a crank 55 and pitman 56, which latter is connected to an arm 57 mounted on the shaft 45. The power shaft 54 is provided with tight and loose pulleys 58 and 59, which latter may be driven from any suitable source of power. A brake 60 is provided on the said shaft 54, to positively stop each press stroke, when desired, and prevent overthrow, this being a common construction on all presses.

The amount of stroke given to the rod 48 is variable by means of a set screw 61 provided in a projection 62 on a sleeve 63 and when said sleeve is connected to the shaft 45, by means to be hereinafter described, the rod 48 is actuated to operate the feed rolls 35 and 36, in manner which will be apparent on viewing Fig. 5. These rolls advance the duplex strip across a support 64 and through a guide 65 arranged above a channel 66 through which caps 67 to be lined are fed (see Figs. 3, 5 and 6). A punch 68 is operated by means of a crosshead 69 operable by the shaft 54. Said punch is yieldingly mounted in a sleeve 71 under the tension of a spring 72 and is adapted to be projected by an arm 73, (Fig. 3) one end of which engages a stop 73' on the frame 38 on the downward stroke of the crosshead 69. The caps 67 (Fig. 6) are fed through a chute 74 into the channel 66 and are advanced therein by

means of a slide 75 having dogs 76 mounted therein and normally held in upper position by springs 77. Said slide is operated from the shaft 45 by means of a cam 78 acting upon a roller 79 carried on an arm 81, the latter being secured to the upper end of a short vertical shaft 82 having bearings in a bracket 83 on the main frame and having secured thereto at its lower end a second arm 84 which is connected by a rod 85 with said slide 75. It will be manifest that covers are advanced on the forward movement of the slide 75 and it is noted that they are held in advanced position by means of pawls 86 and 87, which latter are held under the tension of springs 87', the dogs 76 being allowed to be depressed to position beneath the top of the slide on the return stroke. At the proper time, the punch 68 descends, cutting out a disk from the duplex strip which is designated by the reference character 88 (Fig. 6), said disk being also seated by the punch in the cap which is in position beneath an aperture 89 through which the punch operates. Upon the next forward movement of the slide 75, the lined cover is advanced and a new cover positioned to be lined, the punching operation being so timed with reference to the feeding of the caps that a gasket or liner is punched out and applied to each cover as presented. The lined covers are ejected from the channel 66 into any suitable receptacle.

An important feature of the apparatus consists of a device for controlling the feeding of the liner material so that the strip is not advanced in the absence of a cap in position to be lined, thus preventing the wastage which would otherwise result. A bar 91 is arranged transversely of the channel 66, being supported upon rods 92 secured at their lower ends to a plate 93 (Fig. 5) which is connected by a link 94 and an arm 95 to a shaft 96. Said link 94 is pivoted at 97 and 98 to the plate 93 and the arm 95, respectively. Springs 99 are provided on the rods 92 extending from the plate 93 into sockets 101 in the frame. It will be manifest that said springs tend to draw the rods 92 and the plate 91 downwardly in the channel 66. An arm 102 is mounted on the shaft 96 and connects at its opposite end with a rod 103. Said rod is secured at its opposite end in an arm 104, which is pivoted at 105 to a frame bracket 106 and carries a cam roller 107 in an intermediate projection 108. Said roller is adapted to ride upon a cam 109 which is provided with a recess 111, and it will be manifest that when said roller is riding upon the periphery of the cam, the rod 103 will be held in forward position so that the bar 91 is supported above the channel 66. When the roller reaches the recess 111, the rod 103 is permitted to move rearwardly, drawing down the bar 91. If a cap

67 be present beneath said bar, which it will be noted is positioned at the station immediately preceding the liner applying station, said bar rests thereon and the rod 103 is 5 not permitted to move an appreciable distance.

Referring now to Figs. 5 and 10, it will be observed that the rear end 112 of the rod 103 engages a tail part 113 of a pawl 10 114, which latter engages a ratchet 115 on the shaft 45. The pawl 114 is pivoted on a part 117 and is normally held in engagement with the ratchet 115 by means of a 15 spring-pressed pin 116 engaging the part 113. If no cover be present, the rod 103 is moved rearwardly, disengaging the pawl 114 from the ratchet. If, however, an end be 20 present, said pawl remains in engagement with said ratch and acts upon a part 117 which is rigid with the sleeve 63, causing the latter to turn in clockwise direction, viewing Fig. 10. This lifts the rod 48, which, on the return stroke rotates the roller 35 to advance the strip of liner material. 25 Said roller 35 is connected by gearing 118 with the lower roller 36 so that these rollers cooperate on the return stroke of the rod 48 to feed the strip. In this connection, it will be noted that the part 117 has a shoulder 30 119 engaging the ratchet wheel 115, so that the rocking of the shaft 45 in counter-clockwise direction actuates the sleeve 63 and therewith the rod 48. It will thus be manifest that the feeding is accomplished only 35 when a cap is advancing to the lining station and that the feeding of the liner material and of the caps to be lined is so related that liners may be cut and applied as the successive caps come to rest beneath the 40 punch 68.

The cam 109 is fixed on the shaft 45 so that the recess 111 passes back and forth under the roller 107 this operation being caused by the rod 56. When there is a normal feed of covers, however, the roller cannot be pressed by the springs 99 into said recess because the bar 91 will be sustained by a cover in proper place; but when a cover is not so present the roller will enter the 50 recess and the rod 103 will displace the pawl 114 so that it will not move the part 117 or the sleeve 63 or the rod 48, and no feeding of the lining material 88 will occur, because there is no actuating connection between the sleeve 63 and the shaft 45.

The shaft 45 is mounted in bearings 121 and 122 in frame brackets 106 and 124 and a brake 125, illustrated in detail in Fig. 11, is provided between the bearing 122 and the 60 sleeve 63 to prevent overthrow by momentum. Said brake is attached by a bolt 126 to a depending lug 127 on the bearing 122 and consists of clamping jaws 128 and 129 hinged at 131 and adapted to be tightened 65 by means of a spring bolt 132.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof. 70 75

It is of course apparent that by adding or duplicating one or two mechanisms in my machine a gasket strip composed of more than two materials could easily be produced and I do not wish to limit myself 80 to a duplex strip and I intend the word "duplex" as used by me to comprehend a plurality of layers of material.

I claim:

1. A machine for lining container covers, 85 comprising means for feeding liner material, means for feeding covers to be lined, means for cutting liners from said material and applying them to the covers, and means for preventing the feeding of the liner material 90 in the absence of a cover in position to be lined.

2. A machine for lining container covers, comprising means for feeding liner material, 95 means for feeding covers to be lined, means for cutting liners from said material and applying them to covers, and means for preventing the feeding of the liner material in the absence of a cover in position to be lined, said last-mentioned means comprising a 100 pawl and ratchet device for feeding the liner material, and mechanism controllable by the presence or absence of a cover in predetermined position to control the operation of said pawl and ratchet device. 105

3. A machine for lining container covers, comprising means for combining strips of separate material and for feeding the duplex strip to a lining station, means for feeding covers to be lined to said station, and means for cutting liners from said strip and applying them to successively presented covers. 110

4. A machine for lining container covers, comprising means for combining strips of separate material and for feeding the duplex strip to a lining station, means operable in timed relationship to said strip feeding means for advancing the covers to be lined to said station, and means for cutting liners from said strip and applying them to successively presented covers. 115 120

5. A machine for lining container covers, comprising means for combining strips of different material and feeding the resultant duplex strip with an intermittent motion to a lining station, and means for cutting liners from said strip and applying them to successively presented covers. 125

6. A machine for lining container covers, 130

- comprising means for forming and advancing duplex strips of liner material, means for feeding caps into position beneath said strip, and single means for cutting out and seating liners in said caps.
7. A machine for lining container covers, comprising feeding rolls, means for supplying separate strips of liner material to said rolls, means for applying adhesive to one of
- 10 said strips, means for intermittently operating said rolls to combine the strips and advance the resultant duplex strip to a lining station, means for automatically feeding covers past said station, and means for cutting
- 15 and applying duplex liners to said covers.
8. A machine for lining container covers, comprising feeding rolls, means for supplying separate strips of liner material to said rolls, means for applying adhesive to one of
- 20 said strips, means for intermittently operating said rolls to combine the strips and advance the resultant duplex strip to a lining station, means for automatically feeding covers past said station, means for cutting
- 25 and applying duplex liners to said covers, and means operable in the absence of a cover to be lined for preventing the feeding of said liner material.
9. A machine for lining container covers,
- 30 comprising means for feeding liner material to a liner station, and means for feeding covers to be lined to said station, said first-mentioned feeding means being controllable to prevent the operation thereof in the ab-
- 35 sence of a cover to be lined.
10. A machine for lining container covers, comprising means for feeding liner material to a lining station, means for feeding covers to said station, and means movable into the path of said covers for preventing the feeding of liner material in the absence of a cover at predetermined position in said path.
11. A machine for lining container covers, comprising a punch press, means for feeding liner material and covers to said press, and means for preventing feeding of the material in the absence of a cover in predetermined position.
12. A machine for lining container covers, comprising a punch press, means for feeding liner material and covers to said press, and means for preventing feeding of the material in the absence of a cover in predetermined position, said means comprising a pawl and ratchet device for operation of
- 55 the liner feeding means, and means for disengaging the pawl in the absence of a cover in the said predetermined position.
13. A machine for lining container covers, comprising rolls for feeding liner material to a lining station, a rock shaft connected for intermittent rotation of said rolls, roll driving means on said rock shaft, means for feeding can covers to the lining station, and means operable in the absence of a cover
- 60 in predetermined position in said feeding means to disconnect said driving means from said shaft to prevent operation of the rolls.

JOHN M. HOTHERSALL.
